BAKING FORM

Harry N. Smith, Detroit, Mich., assignor to
American Brakeblok Corporation, New York,
N. Y., a corporation of New York

Application March 23, 1931. Serial No. 524,489

6 Claims. (Cl. 18—34)

This invention relates to forms for supporting composition material for curing in a baking oven and it is particularly adapted for carrying strips of composition friction material for this purpose.

5 The object of the invention is to provide a form for curing strips of composition material which will be light in weight, strong and substantial in construction, and which will hold the material in a desired shape.

10 Another object of the invention is to support the material on the form in a manner which will permit the circulation of heated air between the material and the form to enable uniform curing.

And a further object is to provide a simple 15 means for retaining the material in place on the form.

And a still further object is to provide adjustable means for retaining strips of material to be cured of different lengths.

20 I have illustrated the invention in a simple embodiment in the accompanying drawing and referring thereto

Fig. 1 is a side elevation of the form with material to be cured applied on one end portion 25 thereof and the retainer bar partly broken away.

Fig. 2 is an enlarged transverse sectional view on the line 2—2 of Fig. 1.

Fig. 3 is an enlarged fragmentary longitudinal sectional view through an end portion of the 30 drum.

Fig. 4 is a fragmentary view partly in section taken on the line 4—4 of Fig. 1 showing the adjusting means.

Referring to the drawing the form comprises 35 an elongated transversely curved face plate 5 having end plates 6 and one or more intermediate transverse brace plates 7 corresponding substantially with the end plates, the end plates and the brace plates being provided with edge flanges

40 8 which are spot welded or otherwise secured to the face plate to secure the parts together. Openings 9 are provided in the end and brace plates to lighten the weight. The openings in the end plates form convenient means for grasping the

45 form when it is loaded with composition strips to transfer the form from the loading table to the oven, and the marginal edge about the opening may be turned or flanged at 9' to afford a better hand hold and prevent injury to the operator's hands.

50 The side edges of the face plate project below the bottom edges of the ends and reenforce strips 10 having down-turned ends 11 fit against the bottom edges of the end and brace plates and between the marginal edges of the face plate, these reenforce strips being spot welded

or otherwise secured to the flange at the bottom of the end and brace plates and to the face plate. A sheet 12 of reticulated material, such as wire mesh, is applied to the outer side of the face plate and is snugly secured thereto by bending the 60 marginal edges 13 around the lower edges of the face plate and the ends 11 of the reenforce strips; and the marginal edges of the reticulated sheet may be secured in place in any suitable manner, in addition to bending them as just described, 65 as by means of rivets 12'. Additional reenforce and stiffening strips 14 may be spot welded or otherwise secured to the strips 10. The reticulated sheet is cut away at 15 to expose the face plate 5 on opposite sides thereof and at spaced 70 intervals between the ends of the form and these exposed portions of the face plate have slots 16 therein. Bolts 17 project through these slots and carry spring hooks 18 which are adapted to receive the retainer bars 19 which are preferably 75 channel shape in cross-section and arranged in place with the web in contact with the strips and the flanges outwardly directed. Tubular inserts 19' are secured in the channels to bear against the hooks 18 and pressure is applied to force the 80 bars downward and cause the inserts to spring the hooks outward to create sufficient tension to hold the bars in place. The flat contact face of the web of the channel bar retainer has restricted contact with the surface of the strips and bears 85 against the surface of the strips without indenting or marking them. The inner ends of the bolts are provided with wing nuts 20 which are accessible through the bottom of the form and through the openings 9 in the end plates. The 90 hooks 18 may be adjusted on the face plate by moving the bolts in the slots 16. The invention is particularly adapted, although not exclusively, for holding strips 21 of composition friction material which is sufficiently soft when made to 95 adapt itself to the outer face of the reticulated sheet, or to be easily shaped to fit snugly thereon, and after a desired number of strips 21 are so applied to the form the retainer bars 19 are dropped into the hooks 18 and against the end portions 100 of the strips and are forced downward in operative engagement with the hooks to retain the strips in place while the form is being handled and during the curing operation. The form is preferably made to a shape which will give the 105 strips the proper curvature when the curing operation is finished and the hardened strips are removed from the forms; and these strips may be used in the full lengths in which they are cured or they may be divided into desired lengths. 110

It is important, of course, that the forms should be sufficiently strong, substantial and rigid to maintain their shape so that the strips will have the desired curvature corresponding to the curvature of the forms when the curing operation is finished and my invention provides such a form which is also light in weight and capable of being easily handled. It is also important that the heated air should circulate between the strips during the curing operation and that the strips should be protected from the face plates which may get excessively hot, and this is accomplished with my invention by the provision of the reticulated fabric sheet which forms an air space between the strips and the face plate broken only by the strands of wire forming the sheet and enabling the heated air to circulate between the strips and the sheet sufficiently to prevent uniform curing of the strips.

I have shown the invention in a simple embodiment which has been found satisfactory in actual use but it may be desirable to change the form, construction, proportions and arrangement of parts to adapt the form for other strips and for other material, or for other purposes, and I reserve the right to make all such changes within the scope of the following claims.

I claim:

1. A form for the purpose described comprising an elongated transversely curved face plate, a reticulated metal covering applied to the face plate to receive the material to be cured on the form, means adjustable transversely on the face plate for retaining the material in place on the face plate and including hooks on the form, and longitudinally extending retainer bars adapted to be supported by said hooks in engagement with the material to prevent dislodgment thereof from the form.
2. A form for the purpose described comprising a face plate adapted to support the strips of material to be cured on the form, means adjustable transversely on the face plate for retaining the strips of material in place on the face plate and including hooks on the form and longitudinally extending retainer bars adapted to be supported by said hooks in engagement with the

strips of material to prevent dislodgment thereof to retain the strips on the form.

3. A form for the purpose described comprising an elongated transversely curved face plate adapted to receive and support the strips of material to be cured, oppositely disposed hooks adjustable transversely on said face plate and projecting from the outer side thereof, and longitudinally extending retainer bars adapted to be supported by said hooks in operative engagement with the strips of material to retain the strips on the form.

4. A form for the purpose described comprising an elongated transversely curved face plate adapted to receive and support the strips of material to be cured, said form having oppositely disposed transverse slots, hooks on the outer face of the form adjustably secured in said slots, and longitudinally extending retainer bars supported in said hooks in operative engagement with the strips of material to retain the strips on the form with the faces thereof exposed.

5. A form for the purpose described comprising an elongated transversely curved face plate adapted to receive and support the strips of material to be cured, oppositely disposed hooks adjustable transversely on said face plate and projecting from the outer side thereof, and substantially channel shaped longitudinally extending cross bars adapted to be supported by said hooks with the webs thereof in operative engagement with the strips of material to retain the strips on the form with the faces thereof exposed.

6. A form for the purpose described comprising an elongated transversely curved face plate adapted to receive and support the strips of material to be cured, oppositely disposed spring hooks adjustable transversely on said face plate and projecting from the outer side thereof, substantially channel shaped longitudinally extending retainer bars having tubular inserts secured in the channels thereof to bear against the spring hooks whereby the webs of said retainer bars will be held in operative engagement with the strips of material to retain them on the form with the faces thereof exposed.
